Herman Cohn

BY C. P. Hoepel

ATTORNEY

UNITED STATES PATENT OFFICE.

HERMAN COHN, OF NEW YORK, N. Y.

STRING FASTENER AND ADJUSTER FOR MUSICAL-INSTRUMENT STRINGS.

1,331,863.

Specification of Letters Patent.

Patented Feb. 24, 1920.

Application filed September 6, 1919. Serial No. 322,032.

To all whom it may concern:

Be it known that I, HERMAN COHN, a citizen of the United States, and a resident of the borough of Manhattan, city, county, and State of New York, have invented certain new and useful Improvements in String Fasteners and Adjusters for Musical-Instrument Strings, of which the following is a specification.

10 The present invention relates to improvements in string fasteners and adjusters for musical instrument strings, and particularly I propose to provide a device of this character especially desirable for violin wire 15 E-strings. Wire strings as ordinarily used upon violins are very difficult to adjust to the exact tone because the wooden pegs employed for adjusting the string would not permit of such fine adjustment as is required 20 to properly tune a wire string. It is an object of my invention therefore, to provide means by which the string may be attached to the tail piece of the violin with facility and by means of which it may be adjusted 25 to the very finest degree, and slippage will be prevented. A further object is to enable the loop of the string to be readily secured to the device and easily removed, that is, its removal will not be made difficult by the 30 tight binding of the loop caused by the stretching of the string. Other objects are to provide such means which will not become loose, and will not readily get out of order, and which will be simple in construction 35 and inexpensive to manufacture.

With these and other objects in view, embodiments of my invention are shown in the accompanying drawings and these embodiments will be hereinafter more fully described with reference thereto, and the invention will be finally pointed out in the 40 claims.

In the accompanying drawings,

Figure 1 is a side view of one embodiment of my invention showing a portion of a violin tail piece to which it is attached, and a portion of the wire string;

Fig. 2 is a similar view enlarged, and showing the tail piece in section;

Fig. 3 is a front end view of the device;

Fig. 4 is a top view of the forward portion of the same;

Fig. 5 is a side view of a spring snap button employed in connection with the device; 55

Fig. 6 is a side view of a modified form of construction showing the tail piece in section; and

Fig. 7 is a similar view of a further modified form of construction. 60

Similar reference characters indicate corresponding parts throughout the several figures of the drawings.

Referring to the drawings, and more particularly to Figs. 1 to 5 thereof, the embodiment of my invention shown therein comprises a tubular barrel 10 having a square passage 11 therethrough in which is slidably mounted a rod 12 of square cross section at its intermediate portion, engaging the barrel, and provided respectively at its rear end with a threaded extension 13 and at its forward end with an upstanding hook portion 14. Upon the threaded extension there is provided a nut 15 which bears upon the rear end of the barrel, and by turning moves the hook portion 14 in or out, the pitch of the threads being very small so that the very finest adjustment of the device is possible. 70

Upon the under side of the barrel there is provided a depending post 16 inclined rearwardly to a small degree and adapted to be engaged with the aperture 17 in the tail piece 18 of the violin. 85

The loop 19 of the string 20 is engaged over the hook 14 and the string is drawn tight by the peg in the peg-box of the violin over which the other end of the string is wound. The drawing of the string thus causes the device to lock itself to the tail piece, the forward surface of the post 16 engaging the forward upper edge of the aperture 17 while the rear surface of the post engages the rear lower edge of the aperture, and thereby a wedging action results which increases in its holding effect as the string is drawn tighter, so that the device in order to be attached to the tail piece need only be inserted in the aperture and the drawing tight of the string will secure it in place. 90

The inclination of the tail piece is such relatively to the barrel that the periphery

of the nut 15 is spaced from the surface of the tail piece, and it may therefore be easily turned by the fingers to adjust the string. The tightening of the string in this manner is very easy and positive, and permits of the most delicate adjustment of the string. The direct drawing of the end of the nut into engagement with the end of the barrel by the string will prevent any accidental displacement of the nut, while the low pitch of the threads will permit it to be turned with facility by the finger.

Inasmuch as the hook is of equal cross section or it may with the same purpose be tapered toward its end, it will enable the quick removal of the string when it is desired to renew it, it being only necessary to slip the same off of the end of the hook, and this will not be prevented by the tight binding of the loop upon the hook due to the tightening of the string.

In order to prevent loss of the device from the tail piece, when the string is not drawn tight, I provide an annular groove 21 and a head 22 at the end of the post to which may be secured a spring snap button or head 23, or if desired, the end of the post may be threaded and a nut screwed thereon.

In Fig. 6 I have illustrated a modified form of construction in which the barrel is provided with a post 25 threaded at its end and inclined forwardly, the same being of a size to fit substantially snugly in the aperture of the tail piece, and provided adjacent the barrel with a shoulder 26 engaging the upper surface of the tail piece, while a nut 27 is screwed upon the threaded end and engages the under surface to secure the device in place.

In Fig. 7 I have illustrated another modified form of my invention comprising a plate 30 disposed at the under side of the tail piece and projecting forwardly therefrom, a post 31 provided thereon extending upwardly through the aperture 17, a nut 32 provided upon its upper threaded end securely fixing the device to the tail piece. A lever 33 is pivoted at 34 to the forward end of the plate 30, one arm of the lever extending beneath the said plate where it is engaged at its end by the end of a thumb screw 35 disposed in a threaded hole 36 extending through the post 31, while its other arm is uprightly disposed in front of the tail piece and is provided with a hooked end portion 37 with which the looped end of the string is engaged. By adjustment of the thumb screw, the hooked end of the lever is moved in or out and thereby the string is adjusted. The hook securely holds the string while at the same time it permits of its attachment and removal with facility.

I have illustrated and described preferred and satisfactory embodiments of my inven-

tion but it is obvious that changes may be made therein within the spirit and scope thereof as defined in the appended claims.

I claim:

1. In combination with a musical instrument having a string attachment member, and a string provided at its end adjacent said string attachment member with a loop, a string fastening and adjusting device, comprising means secured to said string attachment member, adjustable means movable in a direction longitudinally of said string and provided at its end adjacent the looped end of said string with a portion bent upwardly and forwardly from its base in a vertical plane, and bent rearwardly from said upwardly and forwardly bent portion, means maintaining said portion immovable from said vertical plane, the point of greatest forward deflection of said portion being engaged by the loop of said string, the part of said portion above said point of engagement of the loop being of no greater cross-sectional dimension than said point of engagement, the end of said portion being free to permit of the removal of said loop upon loosening of said string without movement of said adjustable means and without increasing the diameter of said loop.

2. In combination with the tailpiece of a musical instrument provided with an aperture, a string fastening and adjusting device comprising a member having a longitudinal passage therethrough, another member non-rotatably and slidably engaging said passage, and provided with a screw threaded portion extending therefrom at one end, means at the other end of said member adapted to be engaged by the end of a musical instrument string, a nut engaging said screw threaded portion, having its periphery extending substantially beyond the surface of said first-mentioned member, and adapted by turning to adjust said other member longitudinally of said first-mentioned member, and a post carried by said first-mentioned member extending therefrom at an angle and engaging said aperture of said tailpiece, and adapted to support said first-mentioned member at an inclination to said tailpiece with the end adjacent said nut relatively higher than the opposed end to space the periphery of said nut from said tailpiece to permit of its free turning movement.

3. In combination with a musical instrument tail piece provided with an aperture, a string fastening and adjusting device comprising a member having a longitudinal passage therethrough, another member engaging said passage, adjustment means for adjusting said other member longitudinally of said first mentioned member, means at one

end of said other member adapted to be engaged by the end of a musical instrument string, said adjustment means adapted to tighten said string, a post carried by said 5 first mentioned member of smaller diameter than said aperture of said tailpiece and engaging said aperture in a direction inclined

to the axis of said aperture, tightening of said string adapted to wedge said post in holding engagement with said aperture. 10

In testimony that I claim the foregoing as my invention, I have signed my name hereunder.

HERMAN COHN.
